UNITED STATES PATENT OFFICE.

WILLIAM E. SIDNELL, OF NORWALK, OHIO.

STONE-PLANING MACHINE.

SPECIFICATION forming part of Letters Patent No. 399,705, dated March 19, 1889.

Application filed September 29, 1888. Serial No. 286,788. (No model.)

To all whom it may concern:

Be it known that I, WILLIAM E. SIDNELL, of Norwalk, in the county of Huron and State of Ohio, have invented certain new and useful 5 Improvements in Stone - Planing Machines; and I do hereby declare the following to be a full, clear, and exact description of the invention, such as will enable others skilled in the art to which it pertains to make and use the 10 same.

My invention relates to stone-planing machines in which the stone is mounted on a car, the latter being automatically fed through the machine while the cutting-tool is being 15 reciprocated crosswise to the line of movement of the car. The cutting-tool is connected to a cross-head, and the latter is mounted on ways, the said ways being adjustable vertically to accommodate the thickness 20 of stone being dressed. A channel-bar of considerable length and having an inclined channel or way is connected with the cross-head, in which inclined way operates the free end of a rock-arm that in turn and 25 by means of suitable connecting devices actuates the feed mechanism, the arrangement being such that with the back-stroke of the cross-head the extreme slow feed movement is imparted to the car necessary in moving 30 such heavy body. The cross-head, by means of a pitman, is connected with and actuated by a horizontally-reciprocating slide bar or plunger, the length of the pitman being such that the parts work freely with the cross-head 35 elevated or depressed to the extreme of the vertical adjustment of the ways on which such cross-head reciprocates. The plunger is of peculiar construction, and is actuated by means of a rack and pinion, with adjustable 40 dogs connected with the plunger for shifting the belt, according to the length of stroke desired.

My invention also relates to details of construction, hereinafter described, and pointed 45 out in the claims.

In the accompanying drawings, Figure 1 is a side elevation, portions being broken away to show the construction and to reduce the size of the drawings. Fig. 2 is a plan, partly 50 in section. Fig. 3 is an end elevation, partly in section. Fig. 4 is an elevation in trans-

verse section of plunger and supporting way.

A represents a stone being dressed, and A' the car on which the stone is mounted. As 55 the machine is intended for dressing stone as large as can be shipped and handled, the car is usually ten or twelve feet (more or less) in width, and long enough to receive the longest stone that is likely to be wanted. The 60 car travels on tracks a, and is fed, preferably, with two racks, a', arranged on either side of the car, these racks engaging gears B, the latter being mounted on shaft B', extending under the track. Any suitable gearing may 65 be had for connecting this part of the feed mechanism with ratchet-wheel C—for instance, as shown, where pinion C' is mounted on the same shaft with the ratchet-wheel, such pinion engaging one of the gears B. 70

D D are standards similar in form to those commonly employed on large metal-planers. These standards in pairs are arranged on either side of the track far enough apart to allow the cars to pass between them. A pair 75 of horizontal parallel ways, E, extend from one pair of standards to the other, these ways being connected at the ends by yokes E', and connected with these yokes are screw-rods e, the latter extending, respectively, through 80 the yokes D' of the standards. Beveled pinions F are mounted on these screw-rods, and these pinions, being screw-threaded internally, serve as nuts. These pinions engage pinions F', mounted on shaft f, with cranks 85 f' for elevating or depressing the ways, the screws and shifting mechanism of these ways being well known in connection with metal-planers.

Ways E are provided with bolts e', the latter operating in slots d of the standards, these bolts being tightened after the ways have been adjusted vertically. Upon ways E reciprocates the cross-head G, the latter being connected by pitman G' with a sliding bar or plunger, H. The cross-head is provided with tilting tool-stock G² and screw g, for elevating or depressing the tool-stock, and arranged after the manner of metal-planers, whereby tool g' is made to cut with the forward movement of the cross-head, and is tilted forward and rides back over the work with the rear- 90 95 100

ward movement of the cross-head. Connected with the cross-head is a bar, I, of considerable length, this bar having an inclined channel or way on the one side thereof.

5 J is a rock-shaft, the same being journaled in brackets E², connected on one side of ways E. On rock-shaft J are mounted rock-arms J' and J², extending toward the bar I, and rock-arm J³, extending, usually, in the opposite direction, the latter rock-arm being connected by rod K with pawl-lever L. This lever is of the bell-crank variety, fulcrumed at the elbow, and has attached pawl L' for engaging ratchet-wheel C for feeding the car. Lever L has a slot, l, in which wrist l' may be adjusted lengthwise of the slot, and arm J³ has a series of holes, j, in which wrist j' may be adjusted, and both of which slots and holes may be utilized in regulating the feed. Arms 15 J' and J² are adjustable lengthwise of the shaft J, only one of these arms being used at a time in feeding. If the cross-head is making short strokes, as would be the case in planing a stone of moderate width, arm J' is used.

20 25 For long strokes of the cross-head arm J² is used. These arms, at the free ends thereof, have, respectively, a longitudinal bore in which fits plug M. The plug has a rounded outer end or head adapted to operate in way 30 i. This plug is inserted in either arm, J' or J², that may be wanted for feeding, the other arm meanwhile moving idly. The car is necessarily heavy, and is likely to sustain a load of many tons weight, and the feeding of such 35 heavy bodies must be done slowly. The long bar I and the slight grade of channel i are admirably adapted to such slow feeding. During the return movement of the cross-head the head of plug M enters the upper end of 40 channel i, and the plug in traveling in this channel is gradually depressed, thereby feeding the car very slowly. With the forward movement of the cross-head, the feed mechanism is reversed, the pawl snubbing back 45 over the ratchet-wheel. If the stroke of the cross-head is so long that plug M is drawn out of the channel i, the rock-arm remains stationary, and plug M consequently remains in position to again enter channel i on the return-stroke of the cross-head.

50 Pitman G' is so long that in raising or lowering the ways E to accommodate different thicknesses of stone the "angularity" of the pitman does not affect the free working of the machine. Slide bar or plunger H is also 55 long enough to give the maximum stroke. This plunger is cylindrical, with a flattened upper side, on which latter is attached the rack H' for engaging pinion N, the latter being mounted on shaft N', as is also the master-wheel N². The latter engages pinion n on the driving-shaft n', the latter being provided with necessary band-wheels, (not shown) for reversing the motion. On 60 one side of rack H' the plunger is provided with a longitudinal slot, h, said slot having undercut walls, as shown. Dogs h' are ad-

justed in this slot to engage the belt-shifting mechanism (not shown) in reversing the motion at the end of the stroke. The reverse 70 mechanism may be substantially the same as commonly used on metal-planers, and is therefore not shown, except the dogs aforesaid, and these are of course adjusted lengthwise of the slot to give the different length of stroke. 75 The reverse mechanism, without further description, will be readily understood by any machinist or person likely to engage in building this class of mechanism. The way O, in which plunger H operates, is bored to nicely 80 fit the plunger. There are several advantages of this peculiar arrangement of plunger and way, among which may be mentioned the large wearing-surface, easily kept lubricated, and the self-adjustment of the plunger on its 85 axis to correspond with the bearings of the pitman, by means of which the parts always work freely.

With this machine stones as large as can practically be handled may be dressed; or a 90 series of smaller stones of about the same thickness may be placed on the car and dressed at one operation.

I have reduced my invention to practice, and it is considered a success in every particular.

What I claim is—

1. In a stone-planing machine, the combination, with a car and feed mechanism substantially as indicated, and ways located above 100 and crosswise of the car and having vertical adjustment, of a cross-head bearing cutting tools, said cross-head being mounted on the ways, a plunger operating horizontally and at right angles to the movement of the car, and a 105 pitman connecting the plunger and cross-head for operating the latter at different elevations, substantially as set forth.

2. The combination, with horizontally-reciprocating plunger, the latter being cylindrical and having a flattened upper side, said plunger being connected by pitman with the cross-head of the machine, substantially as indicated, of corresponding cylindrical ways for supporting said plunger, whereby the 115 plunger is self-adjusted on its axis, substantially as set forth.

3. The combination, with cylindrical plunger having a flattened upper side, a corresponding way for supporting such plunger, of rack 120 and dog mounted on the upper side of the plunger, the latter having a longitudinal groove for securing the dog, the latter being adjustable lengthwise of the groove to give the different length of stroke, substantially as 125 set forth.

4. In a stone-planing machine, the combination, with a rock-shaft and attached rock-arm and connecting mechanism, substantially as indicated, for feeding the car by the action 130 of such rock-arm, of reciprocating cross-head and inclined way connected with the cross-head for actuating such feed mechanism, substantially as set forth.

5. In a stone-planing machine, the combination, with a cross-head bearing an inclined way and rock-shaft arranged parallel with the line of the cross-head, such rock-shaft 5 having attached two or more rock-arms that present toward the line of the cross-head, said arms being adjustable lengthwise of the rock-shaft, of removable plug adapted to engage and interchangeable with such rock-arms, said plug having a head adapted to op-

erate in the inclined way of the cross-head, substantially as set forth.

In testimony whereof I sign this specification, in the presence of two witnesses, this 15th day of December, 1887.

WILLIAM E. SIDNELL.
